[57] CLAIM

[21] Appl. No.: 93,901

The ornamental design for a detachable can holder or similar article, as shown and described.

[22] Filed: Nov. 13, 1979

DESCRIPTION

[51] Int. Cl.³ ..... D07—06

FIG. 1 is a perspective view of a detachable can holder or similar article showing my new design;
FIG. 2 is a rear elevational view thereof;
FIG. 3 is a front elevational view thereof;
FIG. 4 is a bottom plan view thereof;
FIG. 5 is a top plan view thereof; and,
FIG. 6 is a side elevational view thereof, the opposite side being a mirror image thereof.
